GEOGRAPHICAL GLOBE CONSTRUCTION

Olaf A. Colberg, Maywood, Ill., assignor to Replogle Globes, Inc., a corporation of Illinois

Application March 9, 1942, Serial No. 433,955

13 Claims. (Cl. 35—46)

The present invention pertains to geographical globe construction, and more particularly to a geographical globe mounting means.

It has been the almost universal practice to make geographical globe supporting meridians of either the full or half type by slush casting, die casting, or other casting processes. Some of these processes required the use of special materials such as zinc alloys which are expensive and also brittle. The brittleness resulted in a high percentage of breakage, both during manufacture of the globe and afterward as in shipment and in use.

The present invention has for its primary objects the provision of a new and improved meridian made of metallic wire. More specifically, the meridian of the present invention is preferably constructed by rolling resilient flat steel wire edgewise and preferably with a curvature such that when the globe is mounted in place on the meridian, the latter exerts an inward force on the globe to secure the two in assembled relation.

Another object of the present invention is the provision of a new and improved meridian of the type described with novel globe mounting means which is detachably held in assembled relation to the meridian by reason of the inward force exerted thereon by the latter.

A further object of the present invention is the provision of new and improved means for securing the meridian to a supporting base.

Other objects and advantages of the present invention will become apparent from the ensuing description, in the course of which reference will be had to the accompanying drawings, in which:

Fig. 1 is a side elevational view of a construction embodying a preferred form of the present invention;

Fig. 2 is a fragmentary enlarged cross-sectional view of the upper globe mounting means, the view being taken along the line 2—2 of Fig. 1;

Fig. 3 is a similar view of the meridian supporting means, the view being taken along the line 3—3 of Fig. 1;

Fig. 4 is a fragmentary enlarged cross-sectional view through the lower globe supporting means and through the meridian supporting means, the view being taken along the line 4—4 of Fig. 3;

Fig. 5 is a view similar to Fig. 2 of another form of globe mounting means;

Fig. 6 is a side elevational view of a modified globe construction;

Fig. 7 is a fragmentary cross-sectional view of

the upper and lower globe mounting means, the view being taken along the line 7—7 of Fig. 6;

Fig. 8 is a fragmentary cross-sectional view of the meridian mounting means, the view being taken along the line 8—8 of Fig. 6;

Fig. 9 is a fragmentary side elevational view illustrating the present invention as applied to a globe of the full meridian type; and

Fig. 10 is a fragmentary cross-sectional view of a further modification of the meridian supporting means.

Referring now to the drawings and more particularly to Figs. 1 to 4, inclusive, it may be seen that a geographical globe 10 of conventional construction is rotatably supported in novel manner by a half meridian 12 of novel construction and secured in novel manner to a base 14. The illustrated base is made of spun metal but it may be made of other material and may take various forms. It is provided with a longitudinal slot 16 (see Fig. 4) of a width to receive the meridian and also a sleeve-like meridian mounting member 18 partially surrounding the meridian and adapted to be secured to both the meridian and base. The sleeve 18 is provided with an arcuate generally channel-shaped upper portion 20 encircling the inner portion of the meridian and also with a pair of opposed arcuate flanges 22, the upper surfaces of which rest against the under side of the top portion of the base 14. This sleeve is passed upwardly through the slot 16 and thereafter secured directly to the base, preferably as by welding the flanges to the base at two places on opposite sides, as indicated by the crossed lines in Figs. 3 and 4.

One of the important features of the present invention resides in the construction of the meridian ring 12. The meridian ring is preferably made of flat steel wire formed into arcuate shape

as by rolling. It should be understood, however, that other types of metals can be utilized as long as the metal possesses sufficient resiliency to perform the functions required of it and which will be described in greater detail hereinafter.

Also it is not necessary that the ring be made of flat wire, although this is the preferred form. The curvature of the meridian is such that the oppositely located ends of the half meridian exert an inward force, i. e., a force tending to compress the globe, thereby to hold both the globe mounting means, indicated generally by the reference characters 24, and the globe in assembled relation relative to the meridian.

The meridian has secured to its peripheral portion a beading or molding 26 of generally channel

shape, the sides of which are bent inwardly slightly as best indicated in Figs. 2 and 3. The molding may be readily applied to the meridian as by welding the same thereto after the meridian has been properly formed. A preferred method of securing the molding to the meridian is to take a straight strip of molding and bend it as it is spot welded directly to the periphery of the meridian.

The curvature of the meridian is dependent primarily upon the diameter of the globe and also the length of the globe mounting means 24. In the construction illustrated in Fig. 1, the curvature of the meridian, when in a relaxed state and prior to the mounting of the globe therein, is such that the upper end lies at a point approximately corresponding to the top of the globe after the globe has been inserted therein. The construction of the meridian in this manner provides not only a meridian that can be constructed economically and is durable, but one which facilitates greatly the assembly of the globe, as will be described in greater detail shortly.

The globe mounting means 24 are of identical construction and they are adapted detachably to be mounted on the meridian and also detachably to receive the globe. Each of the mounting means comprises a short pin 28 adapted to enter the diametrically opposite apertures in the globe. A pair of pin embracing members 30 are secured, as by spot welding, to the pin. The inner portions of the members 30 are bent around the pin, as indicated by the reference characters 32, to provide a more secure and better appearing construction and as shown best in Figs. 2 and 4. The outer portions of the members 30 are flattened as indicated by the reference characters 34 and spaced apart a distance substantially equal to the width of the meridian 12 in order that the meridian may be received therein. The spacing is also such as to leave exposed the outer end of the pin 28.

The meridian is securely held in the mounting means and properly located therein by providing it with opposed slots or notches 36 of a shape to fit over the outer ends of the pins. The construction thus provides an arrangement wherein the resiliency of the meridian is utilized to hold the globe mounting means and the globe in assembled relation to the meridian and likewise an arrangement that greatly facilitates the assembly of the globe.

In assembling the globe, the sleeve 18 is first secured to the base 14 in the manner hereinbefore described. The curved meridian is inserted into the opening defined by the sleeve and the slotted portion of the base and then secured to the sleeve in suitable manner, as by spot welding the same thereto near the ends of the sleeve as indicated by the crossed lines in Fig. 4. The lower mounting means 24 is thereafter placed on the meridian with the pin 28 in registry with the notch 36 in the meridian. The mounting means is thus detachably held in place by reason of the registry of the pin and slot and also by the partial encirclement of the meridian by the flat spaced apart portions 34. A washer 38 may then be placed over the pin to provide a suitable lower bearing for the globe.

The next step in the assembly is the placing of the globe on the lower mounting means. This is accomplished readily by holding the upper end of the globe away from the top of the meridian. While the upper end of the globe is thus held away from the meridian, the upper mounting means 24 may be readily inserted into the open-

ing at the top of the globe. A time dial 40 may be located between the globe and the mounting means as readily ascertainable from Fig. 1. The top of the globe is then swung toward the meridian and the upper end of the meridian is lifted by suitable means to expand it to an extent sufficient for it to pass over the top of the upper mounting means 24. When the meridian is thus expanded, the globe is moved to a position to align the opening in the mounting means with the meridian and the latter is then released so that it may be received in this opening with the pin 28 in registry with the notch 36 in the meridian.

In expanding the meridian, care should be exercised to avoid injury to the globe. A suitable arrangement for expanding the meridian may comprise means extending between the lower portion of the globe and the meridian and other means adapted to be inserted immediately below the top portion of the meridian to force the two ends of the meridian apart. This enables force to be applied to the meridian alone and avoids danger of injury to the globe.

After the meridian globe and mounting means have been assembled in a manner described, they are held in assembled relationship by reason of the inward force applied by the meridian, and which results from the curvature of the meridian being different from the curvature of the globe. The curvature may, of course, be varied to suit the globe diameter and the mounting means, but it is preferred that the force exerted by the meridian not exceed a value that will unduly restrain rotation of the globe on the pins 28.

While it is preferred that the globe mounting means be removably mounted relative to the meridian, this is not necessary as the mounting means may be permanently secured to the meridian. A construction of this nature is illustrated in Fig. 5 wherein the meridian 12 has secured to it, as by welding, a pair of pin embracing members 42 of a construction similar to the members 30 of the first embodiment. These members are likewise secured to the outer ends of a pin 44 located in abutting relationship to the meridian.

In constructing a globe with the mounting means of Fig. 5, the mounting means are first secured to the meridian, then the globe is inserted over the lower mounting means, and, finally, the meridian is expanded to an extent sufficient for the upper pin to enter the opening at the top of the globe. Here, again, the curvature of the meridian should be such that rotation of the globe is not unduly restricted after assembly.

A further modification of the present invention is illustrated in Figs. 6, 7, and 8 to which reference will now be had. According to this modification, the meridian 12, which is constructed in a manner similar to that previously described, is secured to the top of a base 50 by a sleeve-like member 52. The upper end 54 of this member is configured closely to encircle the meridian so that the two can be welded together. The lower portion of the sleeve is widened somewhat, as indicated by the reference characters 56 (see Fig. 8) to receive the molding 26 secured to the periphery of the meridian. The sleeve is also provided with a pair of oppositely extending arcuate flanges 58 resting directly on top of and welded to the base.

In this modification, the globe is mounted on the meridian in a somewhat different manner by means including a rod 60 extending through the globe and having its opposite ends extending into

diametrically opposite apertured channel-like mounting members 62. These members have portions 64 welded directly to the meridian and have their inner portions widened somewhat, as indicated by reference character 66, to enable them to be apertured better to receive the ends of the rod 60.

In constructing and assembling this embodiment of the invention, the meridian is first formed and constructed in the manner previously described. The mounting means 62 are then secured thereto at diametrically opposite points. The meridian receiving sleeve 52 is then secured to the meridian ring and the assembly secured to the top of the base. The next step in the assembly is the insertion of the rod 60 through the globe and the location of the globe on the lower supporting means 62 with the rod 60 extending into the aperture in the latter. The globe is then swung toward the upper mounting means and the meridian expanded in the manner previously described to enable the upper mounting means to be located above the upper end of the rod. Finally, the expanding force is removed to permit the upper end of the meridian to move toward the globe to bring the upper mounting means over the upper end of the rod, as illustrated best in Fig. 7.

It may be noted that in this modification, and also in the modification of Fig. 5, where the mounting means are permanently secured to the meridian, the meridian may be so curved that neither it nor the mounting means are biased sufficiently to bring both the mounting means into contact with the globe. In other words, the biasing force may be such that the globe is suspended relatively freely between the mounting means.

A further modification of the meridian supporting structure is illustrated in Fig. 10 where the meridian 12 is detachably secured to a sleeve-like encircling member 70 by a cam member 72. The member 70 is provided with a pair of substantially centrally located projections or extensions 74 extending below the base 76 through a longitudinal slot 78. The cam is rotatably supported upon the extensions 74 by means of a shaft 80. The member 70 is likewise provided with four oppositely extending flanged portions 82 at both sides thereof and also at both sides of the extensions 74 (only two of the flanges are shown), whereby the sleeve is secured to the base by welding the flanges to the latter.

In mounting the meridian on the base with this construction, the meridian mounting sleeve 70 is first welded to the base and then the meridian is inserted through and finally the cam is operated to force the meridian upwardly into and against the portion of the sleeve encircling the meridian.

The principles of the present invention, while particularly adapted to the construction of globes of the half meridian type, may also be utilized in the construction of a globe of the full meridian type. A globe of this character is illustrated in fragmentary form in Fig. 9. In this construction, the globe mounting means are identical with the globe mounting means 24 of the first described embodiment. The meridian ring, however, is formed into a substantially circular shape. The ring is provided with a notch 84 located substantially centrally of the ends of the meridian and the abutting free ends are provided with half notches 86, which cooperate to form a complete notch for receiving the pin 28 of the upper

mounting means. The flattened portions 34 of the upper mounting means serve to hold the abutting ends of the meridian in place and also give the assembly the appearance of a complete circular meridian.

In assembling a globe of the full meridian type, the method of assembly of the first described embodiment may be followed, i. e., the free ends of the meridian are lifted above the upper mounting means 24 and then allowed to move into the mounting means either individually or simultaneously.

While the present invention has been described in connection with the specific details of preferred embodiments thereof, it should be understood that these details are not to be construed as limitative of the invention except in so far as set forth in the accompanying claims.

Having thus described my invention, what I claim as new and desire to secure by Letters Patent of the United States is:

1. A meridian and mounting for a geographical globe, including in combination, a meridian comprising a strip of resilient metallic wire formed into arcuate shape, and mounting means adapted to extend into the globe at diametrically opposite points for mounting the globe on said meridian, said mounting means including structure partially and removably embracing the meridian and said meridian having a curvature such that said structure is biased toward the globe, whereby the globe, meridian and mounting means are held in assembled relationship.

2. A meridian and mounting for a geographical globe, including in combination, a meridian comprising a strip of flat resilient wire formed edge-wise into arcuate shape, said strip having diametrically oppositely located notches at its inner periphery, and mounting means adapted to extend into the globe at diametrically opposite points for mounting the globe on said meridian, said mounting means including structure partially and removably embracing the inner portion of said meridian and extending into the notches therein, and said meridian having a curvature such that said structure is biased toward the globe, whereby the globe, meridian and mounting means are held in assembled relationship.

3. A meridian and mounting for a geographical globe, including in combination, a meridian comprising a strip of resilient metallic wire formed edge-wise into arcuate shape, and mounting means adapted to extend into the globe for mounting the globe on said meridian, said mounting means including a pin, and pin and meridian embracing means welded to the pin and meridian, and said meridian having a curvature such that the mounting means is biased toward the globe to hold the meridian and globe in assembled relation.

4. A meridian and mounting for a geographical globe, including in combination, a meridian comprising a strip of resilient metallic wire formed edge-wise into arcuate shape, a rod extending through the globe, and means for detachably securing the rod and meridian, said means including opposed channel-like pieces secured to the meridian, said pieces being apertured to receive the ends of the rod when the resilient meridian is expanded diametrically, and said meridian having a curvature such that the channel-like pieces are biased toward the globe to hold the meridian and globe in assembled relation.

5. A half meridian and mounting for a geo-

graphical globe, including in combination, a half meridian comprising a strip of flat resilient wire formed edgewise into substantially semi-circular shape, said strip having diametrically oppositely located notches at its inner periphery, and mounting means adapted to extend into the globe at diametrically opposite points for mounting the globe on said half meridian, said mounting means including structure partially and removably embracing the inner portion of said meridian and extending into the notches therein, and said half meridian having a curvature such that said structure is biased toward the globe, whereby the globe, half meridian and mounting means are held in assembled relationship.

6. A full meridian and mounting for a geographical globe, including in combination, a full meridian comprising a strip of flat resilient wire formed edgewise into substantially circular shape, said strip having diametrically oppositely located notches at its inner periphery, one of said notches being located approximately centrally of said strip and the other being constituted by half notches at the ends thereof, and mounting means adapted to extend into the globe at diametrically opposite points for mounting the globe on said full meridian, said mounting means including structure partially and removably embracing the inner portion of said meridian and extending into the notches therein, and said full meridian having a curvature such that said structure is biased toward the globe, whereby the globe, half meridian and mounting means are held in assembled relationship.

7. A geographical globe mounting, including in combination, a base having a slotted portion at the upper end thereof, a meridian having a width less than that of said slotted portion and mounted in said portion, and means for securing said meridian to said base, said means including a member at least partially encircling the meridian and passing to the underside of said base through said slotted portion, and means for securing said member to said base and to said meridian.

8. A geographical globe mounting, including in combination, a base, a meridian, and means for securing said meridian to the top of said base, said means including an inverted channel-like mem-

ber partially encircling said meridian and having flanges resting on top of said base at opposite sides of the meridian, and means for securing said flanges to said base.

5 9. A geographical globe mounting, including in combination, a base having a slotted portion at the upper end thereof, a meridian having a width less than that of said slotted portion and mounted in said portion, and means for securing said meridian to said base, said means including a member at least partially encircling said meridian and having flanges at opposite sides secured to the top of said base and extensions passing to the underside of said base through said slotted portion, and cam means supported by said extensions and bearing against the meridian.

10 10. A support for mounting a geographical globe on a meridian, including in combination, a pin having an end adapted to extend into a globe, meridian receiving structure secured to the other end of said pin, the outer end of said structure comprising extensions spaced apart to receive the meridian.

11 11. A support for mounting a geographical globe on a notched meridian, including in combination, a pin having one end adapted to extend into the globe and the other end into the notch in said meridian, meridian receiving structure secured to said pin, the outer end of said structure comprising extensions spaced apart to receive the meridian and leaving a section of the pin exposed for cooperation with the notch.

12 12. A support for mounting a geographical globe on a meridian, including in combination, a pin having an end adapted to extend into the globe, meridian receiving structure secured to the other end of said pin, said structure comprising spaced apart extensions closely to receive and adapted to be secured directly to the meridian.

13 13. A support for mounting on a meridian a geographical globe of the type having a rod extending therethrough, including a generally channel-shaped strip having upper side portions spaced apart closely to receive and adapted to be secured to the meridian and lower side portions interconnected by a bottom portion apertured slidably to receive the rod.

OLAF A. COLBERG.

CERTIFICATE OF CORRECTION.

Patent No. 2,368,347.

January 30, 1945.

OLAF A. COLBERG.

It is hereby certified that error appears in the printed specification of the above numbered patent requiring correction as follows: Page 3, second column, line 57, claim 3, for "welded" read --secured--; same line and claim, after the word "meridian" and before the comma insert --for holding the pin and meridian in assembled relation--; and that the said Letters Patent should be read with this correction therein that the same may conform to the record of the case in the Patent Office.

Signed and sealed this 5th day of June, A. D. 1945.

Leslie Frazer
